COMBINED BOBECHE AND CANDLESTICK ORNAMENT

David Saks and Fay Saks, both of 35 Crane Ave.,
White Plains, N.Y.

Filed Apr. 5, 1961, Ser. No. 64,622

Term of patent 14 years

(Cl. D48—2)

FIG. 1

FIG. 2 is an elevational view thereof with several of the support arms omitted for convenience of illustration, and

FIG. 3 is a fragmentary perspective view thereof.

The bulbs are shown in dotted lines for illustrative purposes only.

We claim:

The ornamental design for a combined bobeche and candlestick ornament, substantially as shown and described.
